UNITED STATES PATENT OFFICE

2,205,900

ELECTROMAGNETIC SHUTTLE STOPPING
DEVICEBenjamin W. Jones, Schenectady, N. Y., assignor
to General Electric Company, a corporation of
New York

Application September 7, 1938, Serial No. 228,742

8 Claims. (Cl. 139—185)

This invention relates to power driven looms, more particularly to devices for stopping the shuttle of the loom at the end of each pass through the shed of the warp, and it has for an object the provision of a simple, reliable, and improved stopping device of this character.

For many years a shuttle box at each end of the pass has been utilized for stopping the shuttle, and devices known as picker sticks have been used for smartly rapping the shuttle after it has been stopped in the shuttle box to accelerate it for the return pass in the reverse direction.

The output of looms utilizing means of this character for accelerating and stopping the shuttle is limited to a rather definite value. The use of the shuttle box for stopping the shuttle at the end of the pass interferes with the use of more effective means for accelerating the shuttle to a higher speed than is obtainable at the present time by the use of picker sticks.

Accordingly, a further object of this invention is the provision of an improved means for stopping the shuttle that will make it possible to replace the picker sticks with improved accelerating means thereby to increase the weaving speed and the output of the loom.

Since friction is the means employed in shuttle boxes in stopping the shuttle, and since friction is a quantity that varies with such factors as wear, temperature, and moisture, high shuttle speeds such, for example, as speeds in excess of sixty feet per second cause inaccurate stopping of the shuttle, with the result that the shuttle is not in the correct position to be started in the reverse direction for the succeeding pass. In order to obtain even reasonably accurate stopping of the shuttle by means of a shuttle box at high shuttle speeds, continuous personal supervision and adjustment by an operator are necessary.

Accordingly, a further object of the invention is the provision of an improved stopping means which will stop the shuttle accurately in the correct position and which will reduce the attention of an operator to a minimum.

A further object of the invention is the provision of a shuttle stopping means which will stop the shuttle accurately in the correct position irrespective of the speed of the shuttle.

The use of shuttle boxes, picker sticks, and cooperating mechanism is attended with a great amount of noise. In fact, the noise attending the operation of looms in a weaving mill is a veritable din and perhaps exceeds the noise attending the carrying out of any other industrial operation.

Accordingly, a further object of this invention is the effecting of a substantial reduction in the amount of noise attending the operation of looms.

Other objects will become apparent from a reading of the accompanying specification.

In carrying the invention into effect in one form thereof, means are provided adjacent the warp shed, i. e., the shed formation of warp threads through which the shuttle travels, for producing a magnetic field, and an armature member is mounted for movement in this magnetic field and is so arranged that it is struck by the shuttle at the end of the pass. During the impact of the shuttle with the armature, the kinetic energy of the shuttle is transferred to the armature so that the shuttle is brought to rest and the armature is set in motion. The energy so transferred to the armature is dissipated as a result of the currents produced by movement of the armature in the magnetic field.

For a better and more complete understanding of the invention, reference should now be had to the following specification and to the accompanying drawing of which Fig. 1 is a simple, diagrammatical view in elevation of an embodiment of the invention, Fig. 2 is a plan view of the embodiment of Fig. 1, and Fig. 3 is a plan view illustrating the application of the invention to both sides of the loom to provide stopping the shuttle at each end of the lay.

Referring now to the drawing, a shuttle 10 containing a bobbin of thread, yarn, or other suitable filling material (not shown) is shown at the left-hand extremity of its path of travel. As is well understood, the path of travel of the shuttle lies within the shed formed by the warp threads as a result of the action of the loom harnesses. The warp threads are omitted from the drawing since they do not constitute any part of the present invention. The path of the shuttle is represented by the portion of the lay 11 which underlies and supports the warp while the shuttle is traversing the shed.

Near the end of the path of flight of the shuttle, means are provided adjacent the shed for producing a strong magnetic field. These means are illustrated as an electromagnet 12 provided with a core member 12a having poles 12b and 12c facing each other and separated by an air gap which is crossed by the magnetic flux of the magnet.

An exciting coil 12a surrounds the core member and is connected to a suitable D. C. source of supply represented by the supply line 13. A variable resistor 14 is included in the connections for vary-

ing the excitation of the coil 12_d and the magnetic flux of the magnet.

A suitable armature member is mounted in the air gap between the poles of the magnet. This armature member is an induction disc member 15 provided with pivots 16 and 17 which are journaled for rotation in suitable bearings. The disc is made of a suitable metal such as aluminum or one of the well-known aluminum alloys. The disc 15 is mounted for rotation in the air gap between the poles of the magnet and is provided with a projection 18 which extends into the path of travel of the shuttle so as to be struck by the shuttle at the end of its flight. This projection is made of rubber or other suitable material and is attached to the disc 15 by any suitable fastening means (not shown).

The diameter and thickness of the disc 15 are so determined that the moment of inertia of the disc with respect to its axis of rotation is substantially equal to the moment of inertia of the shuttle at the point of contact with the projection 18, with respect to the axis of rotation of the disc.

Thus in the case of a shuttle weighing one pound and arranged to strike the projection 18 at the periphery of the disc, a disc weighing two pounds would have the same moment of inertia with respect to its own axis of rotation as that of the one pound shuttle with respect to this axis. Assuming the thickness of the aluminum disc as $\frac{1}{4}$ in., the diameter of the disc will be approximately $10\frac{1}{2}$ in.

A stop member 19 is provided in the path of the projection 18 so as to be struck by the projection and thereby to reverse the direction of rotation of the disc. Suitable means illustrated as a spiral spring 20 are provided for returning the disc to its initial position.

With the foregoing understanding of the elements and their organization in the completed device, the operation of the device itself will readily be understood from the following detailed description.

Assuming the shuttle 10 to be at rest at the left-hand extremity of the loom as viewed in the figures of the drawing, it is accelerated to a high speed, e. g. 60 ft. per second by suitable accelerating means 21. The shuttle traverses the warp shed at this speed until it reaches the projection 18 at the opposite end of the shed. The accelerating members of the accelerating means 22 at the opposite end of the shed are withdrawn so that the shuttle passes these accelerating means without coming in contact therewith. The end of the shuttle strikes the projection 18 of the disc 15 which at this time is at rest. The kinetic energy of the shuttle is transferred to the disc 15 and the shuttle is rapidly decelerated to rest. Since the moment of inertia of the shuttle and disc with respect to the axis of rotation of the disc are preferably equal, the shuttle comes to an immediate dead stop just as the cue billiard ball comes to an immediate dead stop when it strikes the stationary ball squarely on a line joining the centers of both balls. Since the accurate stopping of the shuttle 10 by transfer of its kinetic energy to the armature 15 depends only upon the relationship of the moments of inertia of the shuttle and armature, and since the moment of inertia of a body is independent of its speed, the accurate stopping of the shuttle in the correct position is independent of its speed.

As a result of the transfer of the kinetic en-

ergy of the shuttle to the disc 15, the disc is set in rotation and eddy currents are caused to circulate in the disc as a result of the rotation of the disc through the magnetic field between the poles of the magnet 12 and the stored energy of the disc is dissipated in the form of heat produced by these eddy currents.

The stop 19 is preferably positioned so that it will be struck by the projection 18 before the stored energy of the disc is completely dissipated. As a result of the projection 18 striking the stop 19 the direction of rotation of the disc will be reversed, and the dissipation of stored energy will continue during the reverse rotation of the disc. The position of the stop 19 and the strength of excitation of the magnet 12 are so correlated that the stored energy of the disc will be completely dissipated during the reverse rotation and the spring 20 will complete the restoration of the disc to its initial position with the projection 18 extending athwart the path of travel of the shuttle.

During the rotation of the disc, the accelerating means 22 will accelerate the shuttle for the return flight through the shed so that the spring 20 can complete the restoration of the disc to its initial position in which it is left in a reset condition to repeat the operation described in the foregoing.

The weight of the loaded shuttle varies slightly as the filling is withdrawn from the bobbin. Thus, if the moment of inertia of the shuttle is greater than the moment of inertia of the disc by the weight of the filling, the shuttle would tend to pass beyond the point at which it strikes the projection on the disc. To overcome this, suitable means illustrated as a spring actuated clamping means 23 are provided for applying a light friction to stop the shuttle, in the correct position.

As shown in Fig. 3, similar stopping means 24 identical with those described in the foregoing are provided for stopping the shuttle at the end of its flight in the reverse direction.

Although in accordance with the provisions of the patent statutes this invention is described as embodied in concrete form and the principle of the invention has been explained together with the best mode in which it is now contemplated applying that principle, it will be understood that the elements described as shown and described are merely illustrative and that the invention is not limited thereto since alterations and modifications will readily suggest themselves to persons skilled in the art without departing from the true spirit of this invention or from the scope of the annexed claims.

What I claim as new and desire to secure by Letters Patent of the United States, is:

1. Mechanism for stopping a loom shuttle at the end of each pass comprising in combination, an electromagnet arranged adjacent the shed of the warp material, an armature member arranged for rotation in the field of said electromagnet and positionally arranged to be set in motion by said shuttle whereby said shuttle gives up its kinetic energy to said armature and is brought rapidly to rest, and said armature dissipates said transferred energy as a result of its rotation in said magnetic field.

2. Mechanism for stopping a loom shuttle at the end of each pass comprising in combination, a magnet arranged adjacent the shed of the warp near the end of the pass of said shuttle, an armature mounted for rotation in the field

of said magnet and provided with a projection extending into the path of said shuttle to be struck thereby so that said shuttle gives up its energy to said armature member and comes to 5 an immediate stop and said armature is set in motion and dissipates said transferred energy by currents resulting from the movement of said armature in said magnetic field.

3. A device for stopping the shuttle of a loom 10 comprising in combination, a magnet mounted adjacent the warp shed provided with poles facing each other and separated by an air gap, an armature mounted for rotation in said air gap and having a projection extending into the 15 path of said shuttle, said armature and said shuttle having substantially equal moments of inertia with respect to the center of rotation of said armature so that the kinetic energy of said shuttle is given up to said armature and said 20 shuttle brought substantially immediately to a stop as a result of the impact of said shuttle with said projection and said transferred energy is dissipated by the production of eddy currents in said armature as a result of the rotation of 25 said armature in the field of said magnet.

4. A device for stopping the shuttle of a loom comprising in combination, a magnet mounted adjacent the path of the shuttle and having poles facing each other separated by an air gap, 30 a disc mounted for rotation in said air gap and arranged to be set in rotation by an impact of said shuttle so that said shuttle gives up a major portion of its kinetic energy to said disc to stop said shuttle and the energy of said disc is 35 dissipated by eddy currents produced by rotation of said disc in the field of said magnet, and a spring for returning said disc to its initial position.

5. A device for stopping the shuttle of a loom 40 comprising in combination, a magnet mounted adjacent the warp shed and having poles separated by an air gap, a disc armature mounted for rotation in said air gap and arranged to be set in rotation by impact of said shuttle with 45 said disc so that said shuttle gives up a major portion of its kinetic energy to said disc armature thereby to effect stopping of said shuttle and said transferred energy is dissipated by eddy currents produced by rotation of said disc in the 50 field of said magnet, a stop for reversing the direction of rotation of said disc armature before said transferred energy is completely dissipated and means for returning said disc to its initial position after said transferred energy is completely dissipated.

6. A device for stopping the shuttle of a loom comprising in combination, a magnet mounted 55 in proximity to the warp shed and having poles

facing each other and separated by an air gap and a disc armature member mounted for rotation in said air gap and provided with a projection extending into the path of said shuttle so that said disc is set in rotation by impact of said shuttle with said projection, and said shuttle transfers a substantial portion of its kinetic energy to said disc thereby to stop said shuttle, the energy transferred to said disc being dissipated in the form of heat by eddy currents produced by the rotation of said disc in the field of said magnet, a stop arranged in the path of said projection for reversing the direction of rotation of said disc prior to complete dissipation of said transferred energy thereby to 15 provide for returning said disc toward its initial position while said energy is being dissipated, and means for returning said disc to said initial position after said energy is completely dissipated. 20

7. A device for stopping the shuttle of a loom comprising in combination, an electromagnet mounted in proximity to the warp shed and having poles facing each other and separated by an air gap, a disc armature member mounted to 25 rotate in said air gap and arranged to be set in rotation by impact of said shuttle therewith whereby the kinetic energy of said shuttle is transferred to said disc and said shuttle is brought to rest, said transferred energy being 30 dissipated in the form of heat produced from eddy currents generated in said disc as a result of the rotation of said disc in the field of said magnet and means for varying the excitation of said magnet to vary the rate of dissipation of 35 change of kinetic energy in said disc to electrical energy.

8. A device for stopping the shuttle of a loom comprising in combination, an electromagnet mounted in proximity to the warp shed and 40 having poles facing each other and separated by an air gap, a disc armature mounted for rotation in said air gap and provided with a projection extending into the path of said shuttle, said disc armature and said shuttle having 45 substantially equal moments of inertia with respect to the axis of rotation of said disc so that said shuttle gives up a substantial portion of its kinetic energy to said disc and is decelerated as a result of impact with said projection, and the 50 energy transferred to said disc is dissipated as a result of the rotation of said disc in the field of said magnet, and a friction device for absorbing the residue of the kinetic energy of said shuttle thereby to stop said shuttle in a predetermined 55 position.

BENJAMIN W. JONES.
